UNITED STATES PATENT OFFICE.

IRA W. FOLTZ, OF CHICAGO, ILLINOIS, ASSIGNOR TO THE EUREKA SMOKELESS FURNACE COMPANY, OF CHICAGO, ILLINOIS, A CORPORATION OF ILLINOIS.

FURNACE.

1,235,516.

Specification of Letters Patent. Patented July 31, 1917.

Application filed March 5, 1915. Serial No. 12,277.

To all whom it may concern:

Be it known that I, IRA WASHINGTON FOLTZ, a citizen of the United States of America, and a resident of Chicago, county 5 of Cook, and State of Illinois, have invented certain new and useful Improvements in Furnaces, of which the following is a specification.

The main objects of this invention are to 10 provide improved means for increasing the efficiency of furnaces and preventing smoke by causing a more complete consumption of the combustible ingredients of coal; to provide an improved structure and arrangement 15 of baffle wall; to provide a construction for such baffle wall which will permit of ready adjustment to suit beds of coal of different depths and thus serve to obviate the necessity of banking fires or burning 20 fuel at low efficiency when the normal load is reduced; to provide improved means for collecting and conducting the gases of the coal to a place of combustion, to which is also supplied the required amount of air 25 to insure thorough combustion of said gases; to provide a removable or hinged baffle wall between the fire-box and combustion chamber permitting access to the boiler for cleaning 30 the same, while normally serving to prevent the escape of gas before being consumed and direct the gas to a place of intense combustion in the fire; to provide improved means for causing the combustion of gases given off by coal, which means may 35 be readily fitted to furnaces of old types not originally provided with such or similar means; and to provide an improved means removable from the furnace for conducting a draft into sides of a body of coal on the 40 furnace grate and for preventing ashes from accumulating and lessening the draft at the sides of the grate.

An illustrative embodiment of this invention is shown in the accompanying drawings, in which—

Figure 1 is a view in transverse vertical section of a furnace constructed according to this invention.

Fig. 2 is a longitudinal sectional view of 50 the same.

Fig. 3 is a detail in elevation of a removable baffle wall.

Fig. 4 is a side elevation of the baffle wall.

Fig. 5 is a detail of one of the removable 55 side draft units.

Furnaces of the general type shown in the drawings have been furnished with baffle walls above the rear end of the grate, these walls serving to direct the normal draft longitudinally along the grate and also 60 to cause gases which have accumulated in front of said baffle wall to pass downwardly at a place of intense combustion toward the rear of the grate. Said walls were built in or rigidly installed in the furnace and 65 made difficult the cleaning of the boiler flues, usually necessitating removing said baffle wall or to breaking through the rear wall of the furnace in order to permit access to the flues of the boiler.

In the present case, this wall is hinged and removably mounted within the fire-box and therefore may be swung upwardly out of the way to permit access to the boiler flues from the front through the firing door, 70 and may be easily fitted to furnaces of old types whereby their efficiency is increased in the matter of consuming the combustible gases of the coal which, to a large extent, are wasted in some furnaces. Said baffle 75 wall is also made extensible in order that the area of the free space between the grate and the lower end of the baffle wall may be regulated to suit small fires when the furnace is not carrying a large load. 80

The furnace shown in the drawing is of well known construction in regard to the boiler 1, grate 2 and the inclosing walls or brick-work 3. Located above and toward the rear of the grate 2 is a baffle wall 4 90 which, with the crown and side walls or casing 5 of the fire-box, forms a space 6, above and outside the normal draft which passes longitudinally over and through the grate 2 from the openings 7 and 8, and out 95 through the opening 9 at the rear of the grate and below the baffle wall 4. Unconsumed gases rising from the fuel body on the grate 2 collect in space 6 and by the construction of the baffle wall are, in leaving 100

this space, directed downwardly to a point near the rear of the grate 2 where there is ordinarily sufficient heat to cause the combustion of the gases. Under normal conditions, most of the gas circulates through the coal downwardly below the baffle wall to the desired place of combustion, or if there is considerable coal on the grate, some of the gases are conducted downwardly as required through pipes 10 embedded in the baffle wall and having inlets 11 and 12 in the face of the baffle wall and outlets 13 at the bottom of the back of the baffle wall. The baffle wall is also provided with an air passage 14 having outlets 15 near the outlets 13. The air passage 14 is supplied with air through conduits 16 in the water legs of the boiler and which register with the open ends 17 of the passage 14, these conduits 16 communicating with the air space outside of the water legs to which air is conducted by the channel 16^a.

The baffle wall 4 is pivotally supported on the walls of the fire-box, and to this end sockets 18 seated in said walls, receive the ends of a pair of slidable bolts 19 in apertures 20 in the baffle wall. These bolts may be forced outwardly into sockets 18 when the baffle wall is placed in position with the bolts 19 in registry with said sockets. The baffle wall has a groove 24 in its sides and upper edge for receiving an asbestos packing 25. This packing also encircles the ends 26 of the air conduit 14 and bolts 19.

In order to prevent the escape of gas before it is thoroughly heated and consumed, when it is desired to operate the furnace at considerably less than its full capacity and there is little coal on grate 2, the baffle wall 4 is provided with an extension 27 for closing the space between the coal and the lower edge of the baffle wall. The member 27 may be supported on the inner walls of the fire box, independently of baffle wall 4, on lugs 28 in the said walls of the furnace and has a plurality of inclined recesses 29 for cooperating with said lugs, whereby its height above the grate may be regulated. To facilitate the handling and adjustment of member 27, it is provided with apertured ears 30 through which a tool may be inserted when the member 27 is to be removed or vertically adjusted with respect to the baffle wall 4.

For the purpose of increasing the effective grate surface and insuring that the proper quantity of warm air may be supplied to the fuel body, and also for the purpose of preventing accumulation of ashes at the sides of the grate, removable frames or plates 31 are arranged at the sides of the furnace immediately above the grate rests 32. The frames 31 may have flanges 33 at their upper ends for engaging the supporting lugs 34 on the walls of the fire-box, and

are open at their lower ends, with the exception of the space occupied by the spacing legs 35. The side walls of the frames are provided with outlet apertures 36. The air passing up at the sides of the grate around the grate rests may freely enter the frames 31 at the bottom and the frames serve as conduits for the air in its passage from the ash-pit to the sides of the fuel body. This means provides considerable side draft to the fuel body, and ashes are prevented from accumulating over the grate rests and thereby interfering with the draft.

In the operation of the device, the air supply current or draft passes over and through the grate 2, as indicated by the arrows, the point of greatest heat being normally near or to the rear of the lower edge of the baffle wall 4. Such of the gases of the coal as pass along with the draft are, as usual, more or less burned before escaping into the chimney. The gas which arises from the coal cannot escape without first reaching a place of intense combustion, as the only outlet for said gases is around the lower edge of baffle wall 4 or through the conduits 10, these conduits serving to direct said gases to a point of intense combustion nearer the lower end of the baffle. The gases are therefore brought to a high temperature while still within the region of flame. Any additional air which is required to insure the combustion of gases at the baffle wall is furnished through the conduits 16 and 14, the outlets for the latter being 100 the apertures 15 in the rear of baffle 4.

In such instance where the work required by the furnace is considerably less than its normal capacity, the extension 27 of baffle 4 is employed to lessen the space between the lower end of the main baffle and the grate 2 in order that there shall be little, if any, free passage for the escape of unburned gas in the normal line of draft since it would then pass out of the furnace at a velocity 110 too great to insure its thorough combustion.

Although but one specific embodiment of this invention has been herein shown and described, it will be understood that numerous details of the construction shown may be altered or omitted without departing from the spirit of this invention as defined by the following claims.

I claim:

1. A furnace structure having a fire box, combustion chamber and ash pit, a grate structure beneath both said fire box and combustion chamber and separating said box and chamber from said ash pit, a baffle wall structure interposed between said combustion chamber and fire box and extending downwardly to the normal top level of the fuel, said baffle wall having passageways therethrough to permit the passage of gases from the fire box to the combustion chamber.

- ber, means for supplying fresh air to said fire box above the grate, said baffle wall having a fresh air duct communicating with said combustion chamber, and means for 5 supplying fresh air to said duct.
2. A furnace structure having a fire box, combustion chamber and ash pit, a grate structure beneath both said fire box and combustion chamber and separating said box 10 and chamber from said ash pit, a baffle wall structure interposed between said combustion chamber and fire box and extending downwardly to the normal top level of the fuel, said baffle wall having passageways 15 therethrough to permit the passage of gases from the fire box to the combustion chamber, said baffle wall having a fresh air duct communicating with said combustion chamber, and means for supplying fresh air to 20 said duct.
3. A furnace structure having a fire box, combustion chamber and ash pit, a grate structure beneath both said fire box and combustion chamber and separating said box 25 and chamber from said ash pit, a baffle wall structure interposed between said combustion chamber and fire box and extending downwardly to the normal top level of the fuel, said baffle wall having passageways 30 therethrough to permit the passage of gases from the fire box to the combustion chamber, means for supplying fresh air to said fire box above the grate, and means for supplying fresh air for mixing with the gases 35 immediately to the rear of said baffle wall.
4. A furnace structure having a fire box, combustion chamber and ash pit, a grate structure beneath both said fire box and combustion chamber and separating said box 40 and chamber from said ash pit, a baffle wall structure interposed between said combustion chamber and fire box and extending downwardly to the normal top level of the fuel, said baffle wall having passageways 45 therethrough to permit the passage of gases from the fire box to the combustion chamber, means for supplying fresh air to said fire box above the grate, said baffle wall having a fresh air duct communicating with 50 said combustion chamber, and means for supplying fresh air to said duct, said baffle wall except for the passageways above stated closing the space between the combustion chamber and said fire box from the normal 55 top level of the fuel upwardly.
5. A furnace structure having a fire box, combustion chamber and ash pit, a grate structure beneath both said fire box and combustion chamber and separating said box 60 and chamber from said ash pit, a baffle wall structure interposed between said combustion chamber and fire box and extending downwardly to the normal top level of the fuel, said baffle wall having passageways 65 therethrough to permit the passage of gases from the fire box to the combustion chamber, said baffle wall having a fresh air duct communicating with said combustion chamber, and means for supplying fresh air to said duct.
6. A furnace structure having a fire box, combustion chamber and ash pit, a grate structure beneath both said fire box and combustion chamber and separating said box 70 and chamber from said ash pit, a baffle wall structure interposed between said combustion chamber and fire box and extending downwardly to the normal top level of the fuel, said baffle wall having passageways above stated closing the space between the combustion chamber and said fire box from the normal top level of the fuel upwardly.
7. A furnace structure having a fire box, combustion chamber and ash pit, and a baffle 80 wall interposed between said combustion chamber and fire box and extending downwardly into normal contact with the fuel, said baffle wall having channels leading from the fire box to the combustion chamber, and 85 said baffle wall except for the passageways above stated closing the space between the combustion chamber and said fire box from the normal top level of the fuel upwardly.
8. A furnace structure having a fire box, combustion chamber and ash pit, and a baffle 90 wall interposed between said combustion chamber and fire box and extending downwardly into normal contact with the fuel, said baffle wall having channels leading from the fire box to the combustion chamber, and 95 said baffle wall except for the channels above mentioned closing the space between the fire box and combustion chamber from the fuel upwardly to the roof of the furnace.
9. A furnace structure having a fire box, combustion chamber and ash pit, a baffle wall 100 interposed between said combustion chamber and fire box and extending downwardly into normal contact with the fuel, said baffle wall having channels leading from the fire box to the combustion chamber, said 105 channels extending in a downward direction from said fire box to said combustion chamber, and said baffle wall except for the channels above mentioned closing the space between the fire box and combustion chamber from the fuel upwardly to the roof of the furnace.
10. A furnace structure having a fire box, combustion chamber and ash pit, a baffle wall 110 interposed between said combustion chamber and fire box and extending downwardly into normal contact with the fuel, said baffle wall having channels leading from the fire box to the combustion chamber, and said baffle 115 wall except for the channels above mentioned closing the space between the fire box and combustion chamber from the fuel upwardly to the roof of the furnace.
11. A furnace structure having a fire box, combustion chamber and ash pit, a baffle wall 120 interposed between said combustion chamber and fire box and extending downwardly into normal contact with the fuel, said baffle wall having channels leading from the fire box to the combustion chamber, and said baffle 125 wall except for the channels above mentioned closing the space between the fire box and combustion chamber from the fuel upwardly to the roof of the furnace, and means for supplying fresh air to the fire box.

10. A furnace structure having a fire box, combustion chamber and ash pit, a baffle wall interposed between said combustion chamber and fire box and extending downwardly into
5 normal contact with the fuel, said baffle wall having channels leading from the fire box to the combustion chamber, said channels extending in a downward direction from said fire box to said combustion chamber, and
10 said baffle wall except for the channels above mentioned closing the space between the fire

box and combustion chamber from the fuel upwardly to the roof of the furnace, and means for supplying fresh air to the fire box.

15

Signed at Chicago this 3d day of March 1915.
